LESLIE A. RAWSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

INTERCHANGEABLE POST CONSTRUCTION FOR DERRICKS

Application filed January 23, 1929. Serial No. 335,540.

My invention relates to derricks such as are used in the oil producing industry and it particularly concerns an interchangeable post construction therefor.

5 My invention in its broad conception consists of means for securing a post to members of a derrick in such a manner that the post may be rigidly secured in place and may be adjusted in position without removing the post or the securing means from place.

10 My invention in its limited aspect is embodied in the details of construction which will be described in the following description.

15 In order that my invention may be readily understood, I shall briefly refer to oil-well derrick apparatus now in common use.

The common type of derrick consists of a base construction from the corners of which 20 legs are extended upward to the water-table of the derrick where the crown-block is supported. At the edges of the floor or base of the derrick are placed the draw-works, calf-wheel and bull-wheel, which are used during 25 drilling and pumping operations in the well. These apparatus just mentioned require the use of upright posts, which are secured to the base of the derrick and to a girt extending across adjacent legs of the derrick. Ordinarily the posts are secured in place by 30 bolts which extend through holes formed in the base and in the girt. It is ordinarily necessary to adjust the positions of these posts when they are installed and it is sometimes necessary to adjust them at a later time. In the present form of construction it is necessary to remove the attaching bolts and extend them through different holes formed 35 in the base and in the girt. If there are no holes in proper position, the new holes must be drilled or burned by an oxy-acetylene torch.

40 It is an object of my invention to provide a post construction which may be adjusted without removing the posts or the securing means from place. In my invention the securing means is loosened and the posts are slid laterally along the part of the base to which it is secured and along the girt.

45 Another object of my invention is to pro-

vide a means for adjustably securing the post to the derrick which does not require holes to be drilled in the derrick members.

In the ordinary form of posts which are secured in place by bolts it is necessary not only to align the posts horizontally but it is also necessary to align and adjust their vertical position, in view of the fact that the clearance in the holes around the bolts allows the posts to move down slightly in a vertical direction.

55 It is an object of my invention to provide an interchangeable post construction in which the post rests on a base-beam and its position is thus determined.

60 It is a still further object of my invention to provide an interchangeable post construction including hook-bolts which extend around edge flanges of the derrick members for securing the post thereto.

65 It is another object of my invention to provide an interchangeable post construction in which the base-beam and girt are provided with upper and lower flanges and in which the means for securing the post to the base-beam and the girt engages the upper and lower flanges of the base-beam and girt and thus adjustably secures these parts together.

70 Another object of my invention is to provide a combination of the character mentioned in which the end of the post adjacent to the base-beam is provided with an engaging plate and in which the base-beam is provided with a wall against which the engaging plate is clamped by the clamping or securing means.

75 It is a still further object of the invention to provide a combination of the character mentioned in which a stop is secured to the post, this stop engaging the upper flange of the base-beam for determining the vertical position of the post.

80 Another object of the invention is to provide a combination which includes a member having upper and lower flanges, a post having a web lying substantially perpendicular to the member, engaging parts secured to the web having engaging plates adapted to engage the member, and hook-bolts engaging

the upper and lower flanges for securing the post to the member.

It is a further object of the invention to provide a combination of the character mentioned in the preceding paragraph in which the engaging plates engage the wall of the member and in which the hook-bolts clamp the engaging plates against the wall.

Other objects and advantages of the invention will be pointed out in the following description.

My invention may be best understood by reference to the accompanying drawings in which my invention is illustrated.

Referring to the drawings in detail:

Fig. 1 is a perspective view showing the derrick in skeleton and showing the post constructions which embody the features of this invention.

Fig. 2 is an elevational view taken on the line 2—2 of Fig. 1, this view showing the draw-works and the post construction which forms a part thereof.

Fig. 3 is a view of the post construction shown in Fig. 2, this view being taken in the direction of the arrow 3 of Fig. 2.

Fig. 4 is a fragmentary section taken on the line 4—4 of Fig. 3.

Fig. 5 is a section taken on the line 5—5 of Fig. 4.

Fig. 6 is a fragmentary section taken on the line 6—6 of Fig. 3.

Fig. 7 is a section taken on the line 7—7 of Fig. 6.

Fig. 8 is a fragmentary elevational view showing the post construction which supports the calf-wheel or bull-wheel of the derrick equipment.

Fig. 9 is a fragmentary view taken on the line 9—9 of Fig. 8.

Fig. 10 is a fragmentary view taken in the direction of the arrow 10 of Fig. 8.

Referring to Fig. 1 in detail, 11 represents base-beams which form a perimetric frame for the base of the derrick. The base in its entirety includes an inner structure which is not shown in Fig. 1, in view of the fact that it would be confusing. Extending upward from the corners of the perimetric frame are derrick legs 12. Extending across adjacent derrick legs 12 in a horizontal plane and a short distance above the base-beams 11 are girts 13 and 14. Secured to the girt 14 and to the base-beam 11 below it are vertical posts 15, which form a part of the draw-works of the derrick and which embody certain important features of my invention. Secured to the girts 13 which are adjacent to the girt 14 and secured to the base-beams 11 therebelow are posts 16, which support the calf-wheel and bull-wheel of the derrick and which incorporate certain features of my invention.

I will now describe in detail the construction of the posts 15 which form a part of the

draw-works of the derrick. In this description reference will be had to Figs. 2 to 7 inclusive.

As shown best in Fig. 6, the base-beam 11 is in the form of a channel and has a vertical wall 20, and upper and lower inwardly extending flanges 21 and 22 which provide outer horizontal faces 23. The girt 14, as best illustrated in Fig. 4, includes a channel 25 having an upright web 26 and upper and lower flanges 27 and 28. Secured to the web 26 adjacent to the flanges 27 and 28 are channels 29 and secured to the edges of the channels 29 remote from the channel 25 is a plate 30. The girt 14 therefore consists of a hollow bar of rectangular cross-section having external flanges 27 and 28 at the inner part thereof.

Referring now to Figs. 6 and 7, I will describe the construction of the means for securing the lower end of each post 15 to the adjacent base-beam 11. In the first place, I prefer to form each post 15 from an I-beam having a web 32 which extends in a plane at right angles to the plane in which the adjacent base-beam 11 extends. The lower end of the post 15 is notched at 33 so as to provide a vertical wall 34 which preferably extends parallel to the wall 20 and may or may not contact the web, as will be pointed out later. The posts 15 incline inward at their upper ends and it is therefore necessary to provide the notch 33 so that a satisfactory joint may be made.

Placed on opposite sides of the web 32 are engaging members in the form of angles 35. The angles 35 have legs 36 which engage opposite sides of the web 32 and are secured thereto by rivets 38. The angles 35 also have legs which are called engaging plates 39, which extend outward from the web 32 in opposite directions and in a plane substantially at right angles thereto. The engaging plates 39 are parallel to the wall 20 and are adapted to be clamped against the wall 20. It is therefore immaterial whether or not the wall 34 of the post 15 engages the wall 20.

In order to determine the vertical position of the post 15 I provide a stop member 41, which consists of a leg 42, secured to the engaging plate 39 by rivets 43. A horizontal portion 44 extends horizontally therefrom and is adapted to engage the outer face 23 of the upper flange 21 of the base-beam 11. If desired, the stop 41 may be secured to the web 32 and the portion 44 may extend horizontally in a direction at right angles to the plane of the paper and if desired a pair of stops 41 may be provided, as is shown in the drawings.

For the purpose of securing the parts in the position shown in Figs. 6 and 7 I provide upper and lower hook-bolts 46. The hook-bolts 46 each have a hook-shaped head 47 and a rod portion 48. The hook-shaped head 47

extends around the inner edge of the flange 21 or 22 and the rod portion 48 extends in engagement with the outer face 23 of the flanges 21 or 22. The rod portions 48 extend through 5 openings 49 and nuts 50 are screwed on to the ends thereof in order to clamp the parts together. It will be seen that there are two upper hook-bolts and two lower hook-bolts which extend through the openings 49 in the 10 engaging plates 39. When the nuts 50 are advanced into the positions shown in Figs. 6 and 7 the engaging plates 39 will be rigidly clamped against the wall 20 of the base-beam and a rigid connection will be provided.

15 The upper end of the post 15 and the means for securing it to the girt 14 is shown best in Figs. 4 and 5. Extending upward from the upper end of the post 15 are members preferably in the form of substantially vertical 20 angles 55. The angles 55 have legs 56 which are secured by rivets 57 to the web 32. Extending outwardly at right angles to the web 32 are legs or engaging plates 58 of the angles 56. The engaging plates 58 are adapted 25 to contact the wall 26 of the channel 25.

Upper and lower hook-bolts 59 are adapted to secure the upper end of the post 15 to the girt 14. The hook-bolts 59 have hook-shaped heads 60 and rod portions 61. The hook-shaped heads 60 extend around the outer edges of the flanges 27 and 28 and the rod portions 61 extend in contact with the outer faces of these flanges. Openings 62 are provided in the engaging plates 58 and the rod portions 61 extend through these openings and have nuts 64 screwed on the ends thereof for clamping the engaging plates 58 against the wall 26 of the channel 25. This constitutes the post construction and the means for adjustably securing the post construction to the base-beam of the derrick and to the girt 14.

40 When it is desired to adjust the horizontal position of the post 15 the nuts 50 and 64 are loosened so that the hook-bolts 46 and 59 will not grip the base-beam and the girt. It is then possible to easily slide the post 15 horizontally in either direction and into the correct position. It is possible to vertically align the post by moving either the upper end 45 or the lower end. It is possible to adjust these posts by moving them horizontally either a fraction of an inch or an inch or more.

The draw-works of which the posts 15 are 55 a part may be of any standard construction including bearings 66 and 67, which support shafts 68 and 69 respectively, on which various mechanisms of the derrick are supported. Extending from the upper end of each post 60 adjacent to the angles 56 are angles 70 which support an auxiliary horizontal channel 71, which may support a shifting mechanism 72 of the draw-works. Since this mechanism 65 does not form a part of the invention, details thereof will not be described.

I will now refer to Figs. 8, 9, and 10 and describe the details of the invention which are embodied in the posts 16, which are used in either the bull-wheel or calf-wheel structure.

The posts 16 are preferably made from I-beams having webs 75 which extend in planes at right angles to the adjacent base-beam 11. Extended downward from the lower end of each post 16 are engaging members in the form of angles 76. The angles 76 have legs 77 which engage the web 75 and are secured thereto by rivets 78. Extending outward from the web 75 in opposite directions are legs in the form of engaging plates 79, which are adapted for engagement with the wall 20 of the adjacent base-beam 11. It should be noted that in this form of the invention the lower end of the post 16 terminates above the base-beam 11 and the engaging parts 77 extend downward therefrom. In order to rigidify the engaging member 77 a block 81 is secured between the lower ends thereof. It will be seen that this space is necessarily provided between the legs 77, in view of the fact that they are disposed on opposite sides of the web 75. Secured to the post 16 are stops 82. The stops 82 have vertical legs 83 secured to the web 75 by rivets 84 and have horizontal legs or portions 85 which project outward in opposite directions and are adapted to engage the outer face 23 of the flange 21 of the adjacent base-beam 11.

For the purpose of securing the lower end of the post 16 to the base-beam I provide hook-bolts 87, which are of the same construction as used in the form of the invention shown in Figs. 2 to 7 inclusive. These hook-bolts 87 have heads 88 which extend around the flanges 21 and 22 and have rod portions 89 which extend through the engaging plates 79. Nuts 90 are screwed onto the ends of the rod portion 89 for clamping the parts together.

The upper end of the post 16 rests below the adjacent girt 13. The girt 13 may be made from a channel or may be made from an I-beam, as shown. The girt 13 when in the form of an I-beam provides an upper flange 93 and a lower flange 94 providing outer faces 95. Secured to the post 16 and extended upward therefrom are engaging members in the form of angles 96. The angles 96 have legs 97 which are secured to the web 75 by bolts 98. Provided between the upper ends of the angles 96 is a spacing plate 99. Extending outward from the web 75 in opposite directions are legs of the angle 96 which are in the form of engaging plates 101. The engaging plates 101 are adapted to engage adjacent edges of the flanges 93 and 94.

Positioned below the girt 13 are upper stops 102. The upper stops have legs 103 secured to the web 75 by rivets 104 and have horizontal portions or legs 105 which extend horizontally outward in opposite directions.

These horizontal portions 105 are adapted to engage the outer face of the lower flange 94 for determining the vertical position of the post 16.

5 For securing the upper end of the post 16 to the girt 13 my invention provides hook-bolts 107 having heads 108, which engage around edges of the flanges 93 and 94, and rod portions 109 which extend in contact with the outer faces 95 of the flanges 93 and 94 and through openings 110 provided in the engaging plates 101. Nuts 111 are screwed onto the ends of the rod portions 109 for clamping the engaging plates 101 against the flanges 93 and 94 of the girt 13.

10 In this form of the invention the construction is slightly different but the principle is the same. By loosening the nuts 90 and 111 the gripping action of the hook-bolts 87 and 20 107 is released and the post 16 may be slid horizontally on the base-beam and the girt 13.

15 In this application I have illustrated two forms in which my invention may be embodied. It should be readily understood that 25 various modifications may be made without departing from the invention. I therefore desire my invention to be interpreted in the light of the following claims.

I claim as my invention:

30 1. In a derrick including an interchangeable post construction, the combination of: a base-beam; a girt; a post extending from said base-beam to said girt; and means for securing said post to said base-beam and said 35 girt in such a manner that said post may be moved laterally along said base-beam and said girt without removing said post from said base-beam and said girt and without removing said means from place.

40 2. In a derrick including an interchangeable post construction, the combination of: a base-beam having upper and lower flanges; a girt having upper and lower flanges; a post adapted to engage said base-beam and said 45 girt; and means engaging said upper and lower flanges of said base-beam and said girt for adjustably securing said post to said base-beam and said girt.

50 3. In a derrick including an interchangeable post construction, the combination of: a base-beam having upper and lower flanges; a girt having upper and lower flanges; a post adapted to engage said base-beam and said 55 girt; and means engaging said upper and lower flanges of said base-beam and said girt for adjustably securing said post to said base-beam and said girt, said means comprising hook-bolts adapted to extend around the edges of said upper and lower flanges.

60 4. A combination as defined in claim 2 in which the end of said post has an engaging plate, and said base-beam has a wall parallel thereto, said means clamping said engaging plate and said wall in contact.

65 5. In combination in a derrick: a member

having upper and lower flanges; a post having a web lying substantially perpendicular to said member; engaging parts secured to said web, having engaging plates adapted to engage said member; and hook-bolts engaging said upper and lower flanges and said engaging plates for securing said post to said member.

70 6. In combination in a derrick: a member having upper and lower flanges and a wall; a post having a web lying substantially perpendicular to said member; engaging parts secured to said web, having engaging plates adapted to engage said wall of said member; and hook-bolts engaging said upper and lower flanges and said engaging plates for securing said post to said member and clamp said engaging plates against said wall.

75 7. In combination in a derrick: a member having upper and lower flanges; a post having a web lying substantially perpendicular to said member; engaging parts secured to said web, having engaging plates extending from said web in opposite directions and at right angles thereto adapted to engage said member; and hook-bolts engaging said upper and lower flanges and said engaging plates for securing said post to said member.

80 8. In combination in a derrick: a member having upper and lower flanges and a wall; a post having a web lying substantially perpendicular to said member; engaging parts secured to said web, having engaging plates extending from said web in opposite directions and at right angles thereto adapted to engage said wall of said member; and hook-bolts engaging said upper and lower flanges and said engaging plates for securing said post to said member and clamp said engaging plates against said wall.

85 9. In combination in a derrick: a member having upper and lower flanges and a wall; a post having a web lying substantially perpendicular to said member; engaging parts secured to said web, having engaging plates extending from said web in opposite directions and at right angles thereto adapted to engage said wall of said member; and hook-bolts engaging said upper and lower flanges and said engaging plates for securing said post to said member and clamp said engaging plates against said wall.

90 10. In combination in a derrick: a member having upper and lower flanges; a post having a web lying substantially perpendicular to said member; engaging parts secured to said web, having engaging plates adapted to engage said member; hook-bolts engaging said upper and lower flanges and said engaging plates for securing said post to said member; and a stop secured to one of said engaging plates, and engaged with said upper flange.

95 11. In combination in a derrick: a mem-

ber having upper and lower flanges; a post having a web lying substantially perpendicular to said member; engaging parts secured to said web, having engaging plates adapted to engage said member; hook-bolts engaging said upper and lower flanges and said engaging plates for securing said post to said member; and a stop secured to one of said engaging plates, and engaged with said upper flange.

5 12. In combination in a derrick: a member having upper and lower flanges and a wall; a post having a web lying substantially perpendicular to said member; engaging parts secured to said web, having engaging plates adapted to engage said wall of said member; hook-bolts engaging said upper and lower flanges and said engaging plates for securing said post to said member

15 20 and clamp said engaging plates against said wall; and a stop secured to one of said engaging plates, and engaged with said upper flange.

25 13. In combination in a derrick: a member having upper and lower flanges and a wall; a post having a web lying substantially perpendicular to said member; engaging parts secured to said web, having engaging plates extending from said web in opposite 30 directions and at right angles thereto adapted to engage said wall of said member; hook-bolts engaging said upper and lower flanges and said engaging plates for securing said post to said member and clamp said engaging plates against said wall; and a stop secured to one of said engaging plates, and engaged with said upper flange.

35 14. A combination as defined in claim 2 in which the end of said post has an engaging 40 plate and a stop attached to said engaging plate.

45 15. A combination as defined in claim 2 in which the end of the post has an engaging plate and a stop attached to said engaging plate, said stop engaging said base-beam.

50 16. A combination as defined in claim 2 in which the end of said post has an engaging plate, said means clamping said engaging plate to said base-beam.

55 17. In testimony whereof, I have hereunto set my hand at Los Angeles, California, this 19 day of January, 1929.

LESLIE A. RAWSON.
